UNITED STATES PATENT OFFICE

JOHN A. KIMBALL, OF TAYLORVILLE, ILLINOIS

CASTER

Application filed December 19, 1930. Serial No. 503,588.

This invention relates to casters and has especial relation to casters for use upon furniture.

An object of the invention is to provide a caster which may be rotatably mounted within the leg of an article of furniture so that the said article may be moved forward and reverse in a direct line without requiring a roller to pivot on its vertical center, as is necessary in the use of casters of the ordinary type. This pivoting of the roller on its vertical center results in twisting and frequently tearing a rug or carpet, as well as marring the surface of a floor where the furniture is moved over a bare floor, and the present invention has been designed for the purpose of overcoming these disadvantages.

Another object of the invention is the provision of a caster having a flat roller which is freely movable in a direct horizontal line upon opposite sides of the vertical center of the caster and wherein the weight of a supported article of furniture is transferred from the roller trunnions to the periphery of the roller during such movement.

With the above and other objects in view, the invention further includes the following novel features and details of construction, to be hereinafter more fully described, illustrated in the accompanying drawings and pointed out in the appended claims.

In the drawings:—

Figure 1 is an elevation of the invention shown attached to the leg of an article of furniture with the leg in section, the view also showing the reverse position of the roller by dotted lines.

Figure 2 is a vertical sectional view showing the support transferred to the periphery of the roller.

Figure 3 is an edge view of the invention per se.

Referring to the drawings in detail where-in like characters of reference denote cor-

responding parts, the reference character 10 indicates the opposite parallel sides of a carriage, while 11 indicates a top plate which connects the upper edges of the sides 10. This top plate is provided with an opening 12 for the passage of a shank 13 whereby the caster may be attached to the leg 14 of an article of furniture. The leg is provided with a socket 15 which receives a split sleeve 16, the latter having a toothed flange 17 whereby this sleeve may be secured to the leg 14. The shank 13 is provided with a head 18 for insertion in the split sleeve whereby the caster may be attached as is usual in devices of this character.

The shank 13 carries a ball race 19 for antifriction balls 20 and these balls bear upon the top plate 11 while the ball race bears against the under face of the flange 17 so that the cage may be freely rotated about its vertical center.

The side plates 10 of the cage are provided with horizontally disposed elongated slots 21 and these slots are adapted to receive trunnions 22 which extend from opposite sides of a roller 23. The upper edges of the slots 21 bear upon the trunnions 22 and the sides 10 are provided with outwardly disposed reinforcing flanges 24 at opposite ends of the slots which provide bearings for the trunnions 22. The upper walls of the slots 21 extend upwardly as shown at 25 from points spaced inward from the opposite ends of the slots, so that when the trunnions move inward from beneath the bearing flanges 24, the periphery of the roller 23 will have engaged a head 26 which is carried by the shank 13, so that the weight will be transferred from the trunnions to the periphery of the roller 23. By providing the head 26, a reinforced bearing surface for the roller 23 is provided at this point.

When an article of furniture to which the caster is attached is moved in the direction of the arrow *a* in Figure 1 of the drawings,

the roller 23 will occupy the position shown in full lines in said figure. Should it be desired to move the article of furniture in a reverse direction, the trunnions 22 of the roller will move longitudinally through the slot 21, the weight being supported upon the trunnions until the latter reach approximately the beginning of the curved portion 25 of the slot. The periphery of the roller will 10 then have engaged the head 26, so that the weight will be transferred from the trunnions to the periphery of the roller and the latter will freely roll to the opposite end of the cage with the trunnions engaging with 15 in the opposite ends of the slots 21 as shown by the dotted line position in Figure 1. In Figure 2 the roller 23 is shown as supporting the weight.

The invention is susceptible of various 20 changes in its form, proportions and minor details of construction and the right is herein reserved to make such changes as properly fall within the scope of the appended claims.

25 Having described the invention what is claimed is:—

30 1. In a caster, a cage, means to mount the cage for horizontal rotary movement, a floating roller supporting the cage, and means to transfer the support of the cage from the trunnions of the roller to the periphery thereof.

35 2. In a caster, a cage comprising spaced parallel side walls having longitudinally disposed slots therein and a top wall connecting the side walls, a roller having its trunnions extending into said slots and supporting the cage, means to mount the cage for horizontal rotary movement, and means to transfer the 40 support of the cage from the trunnions to the periphery of the roller.

45 3. In a caster, a cage comprising spaced parallel side walls having longitudinally disposed slots therein and a top wall connecting the side walls, a shank extending upwardly from the cage intermediate the length of the slots and having a head disposed within the cage, a roller having its trunnions extending into said slots and supporting the cage, and 50 means to transfer the weight from the trunnions to the periphery of the roller.

55 4. In a caster, a cage comprising spaced parallel side walls having horizontally extending slots therein and a top wall connecting the side walls, a shank extending upwardly from the cage intermediate the length of the slots and having a head disposed within the cage, a roller having its trunnions extending into and freely movable throughout the 60 length of said slots and supporting the cage, and means to transfer the weight from the trunnions to the periphery of the roller.

65 5. In a caster, a cage comprising spaced parallel side walls having horizontally extending slots therein and a top wall connect-

ing the side walls, a shank extending upwardly from the cage intermediate the length of the slots and having a head disposed within the cage, a roller having its trunnions extending into and freely movable throughout the 70 length of said slots and supporting the cage, and said slots having their upper walls curved for a distance spaced from the ends of the slots to transfer the weight from the trunnions to the periphery of the roller.

In testimony whereof I affix my signature.

JOHN A. KIMBALL.
